United States Patent Office.

JOEL C. JACKSON, OF ROCHESTER, NEW YORK, AND FREDERICK J. JACKSON,
OF DANBURY, CONNECTICUT.

Letters Patent No. 77,491, dated May 5, 1868.

IMPROVED BEDSTEAD-FASTENING.

The Schedule referred to in these Letters Patent and making part of the same.

TO ALL WHOM IT MAY CONCERN:

Be it known that we, JOEL C. JACKSON, of Rochester, in the county of Monroe, and State of New York, and FREDERICK J. JACKSON, of Danbury, in the county of Fairfield, and State of Connecticut, have invented, made, and applied to use a certain new and useful Improvement in Fastenings for Bedsteads; and we do hereby declare the following to be a full, clear, and exact description of the said invention, reference being had to the annexed drawing, making part of this specification, wherein—

Figure 1 is a section of said fastening, vertically, through the post and end of the rail, and

Figure 2 is a view endwise of the rail and fastenings.

Similar marks of reference denote the same parts.

The nature of our said invention consists in a pair of inclined hooks, formed with round screw-shanks, screwed into the end of the rail, the projecting ends standing at an acute angle to the end of the bedstead-rail, and entering similarly-inclined holes bored into the posts, so that the side rails and posts are simply hooked together, and can be separated with facility, but at the same time the weight upon the side-rails tends to force the hooks further into the posts, and thereby bring the side-rails and posts more closely and firmly together.

In the drawing, *a* represents a portion of the post, *b* a portion of the rail, of any usual or desired character. *c c* are the hooks, formed with the threaded shanks, *c'*, screwed into the end-piece of the rail *b*.

The hooks *c c* stand at an inclination downwards from the end of the rail, and in the post *a* holes are bored at a corresponding angle, so that the hooks *c* enter the posts at an acute angle, and form a very secure and reliable fastening, that tightens under pressure, but by lifting or knocking up the ends of the rails, the bedstead is taken apart with great facility.

The hooks may be round or polygonal, and, if desired, there may be more than two hooks employed at the ends of each rail.

What we claim, and desire to secure by Letters Patent, is—

The bedstead-fastening, formed of the inclined hooks *c*, with their threaded shanks, *c'*, screwed into the ends of the rail, as set forth, and entering corresponding holes in the posts, as specified.

In witness whereof, we have hereunto set our signatures, this twenty-third day of March, A. D. 1868.
